UNITED STATES PATENT OFFICE.

RALPH BURT WELSH, OF BURKBURNETT, TEXAS.

DEEP-WELL PUMP.

Application filed July 2, 1923. Serial No. 649,137.

My invention relates to improvements in deep well pumps, and it consists in the combinations, constructions, and arrangements herein described and claimed.

6 An object of my invention is to provide a deep well pump that is adapted to automatically take up the wear between the plunger and the cylinder wall, whereby leakage between these parts is prevented.

10 A further object of my invention is to provide a device of the type described that has a packing which is adapted to prevent sand from becoming lodged between the plunger and the barrel.

15 A further object of my invention is to provide a device of the type described, which is simple in construction, durable and efficient for the purpose intended, and which is not likely to get out of order easily.

20 Other objects and advantages will appear in the following specification, and the novel features of the invention will be particularly pointed out in the appended claims.

My invention is illustrated in the accompanying drawings forming part of this application, in which

Figure 1 is a vertical section through the device, portions thereof being shown in elevation,

25 Figure 2 is a section along the line 2—2 of Figure 1,

Figure 3 is a detail view of a modified form of the packing-compressing member, and

30 Figure 4 is another modified form of a packing-compressing member.

In carrying out my invention I provide a deep well pump that consists of a housing 1 having longitudinally extending rows of teeth 2 cut in its inner surface. A housing 3 is permanently secured to the housing 1 and has a smooth inner wall 4. A coupling 5 secures the pump to the well tubing. A plunger 7 is slidably disposed in the housings 1 and 3 and extends into the pump barrel extension 8. The extension 8 is secured to the housing 3 by means of a coupling 9.

I provide a packing 10 that is disposed in the housing 3, this packing being supported by a ring 11, and in turn supporting a sleeve or ring 12. The sleeve 12 has a tapered under surface 13, this surface bearing against the packing 10. It is obvious that the packing will become worn through use, and I therefore provide a novel means for automatically compressing the packing to a

greater extent so that the packing always fills the space between the surface 4 and the plunger 7. A collar 14 is slidably disposed upon the plunger 7 and bears against the top of the sleeve 12. The collar has recesses 15 in its outer surface, these recesses receiving pawls 16. The pawls 16 have teeth 17 that are adapted to engage with the teeth 2 to prevent upward movement of the collar 14 with respect to the housing 1. It will be noted that the teeth 2 and 17 are shaped so as to permit downward movement of the pawls with respect to the housing 1, but will prevent upward movement of the pawls. 70 Springs 18 disposed in the recesses 15 yieldingly engage with the pawls 16.

From the foregoing description of the various parts of the device, the operation thereof may be readily understood. The plunger is connected to rod 19 that extends to the top of the well. The rod 19 is actuated in the ordinary manner so as to pump oil into the tubing 6. The plunger 7 is provided with a valve cage 20 at its upper end, the cage projecting beyond the outer surface of the plunger and being adapted to abut the top of the collar 14. During the operation of the device, the cage 20 strikes the collar 14 each time the plunger is moved downwardly. In oil pumping machinery, the lower limit of movement is determined by the cage 20 striking the collar 14, and this limit changes as the collar is moved downwardly. The depth of the packing 10 is not so great as to prevent the rods 19 from causing the sleeve 12 to keep the packing compressed until the last bit is used. The collar in turn drives the sleeve 12 downwardly against the packing 10 so as to take up the wear between the wall 4 and the plunger 7. The collar 14 is held after being driven downwardly by means of the pawls 16 engaging with the teeth 2. In this manner any wear is automatically taken up as the device operates. The sleeve 12 can be moved downwardly the entire length of the packing 10 if the packing is worn away to this extent, the pawl 16 holding the sleeve and collar in the lowermost position to 95 which they are moved by the cage 20. An inlet valve 21 is carried by the extension 8. The plunger 7 moving upwardly opens the valve 21 and in moving downwardly opens the valve 20.

100 The compressing of the packing 10 so as to make a leak-proof joint between the

wall 4 and the plunger 7 prevents the oil from leaking back into the well, which leakage causes the oil to "cut up," thus preventing the oil from being used as first-class oil. The packing 10 also prevents sand from becoming disposed between the plunger and the wall of the cylinder, thereby greatly increasing the life of the pump. Moreover, the time and labor saved in working the pump all of the time instead of having to remove the pump from the well from time to time so as to fix the same is a big factor and also saves a large quantity of oil which would be lost during the time consumed in fixing the pump. In Figures 3 and 4 I have shown a modified form of the pawls 16. In Figure 3 I have shown the pawls as consisting of springs 30 that are adapted to engage with the teeth 2 to prevent upward movement of the collar 14 but to permit downward movement of the collar. In Figure 4 I have shown the pawls 40 as being received in the recesses 41 that have cam surfaces 42. A spring 43 bears against the pawls 40 and holds the pawls in engagement with the teeth 2.

In case the sleeve 14 is not moved down rapidly enough to compress the packing as the latter is worn, I can lower the pump rod so as to have the sleeve support the weight of the rod instead of the pumping mechanism at the top of the well. The weight of the rod is sufficient to move the sleeve 14 downwardly to compress the packing 10. This operation can be repeated once or twice a month or as often as needed. It will be noted that some wells have more floating sand than others which wears out the packing faster than the sand does in other wells.

I claim:

1. A deep well pump comprising a housing having longitudinally extending rows of teeth in its interior wall, a plunger having an enlarged portion at its uppermost end and arranged for movement in a reciprocatory path within said housing, a disk,

packing carried by said disk, said packing being disposed between said plunger and said housing, a sleeve slidably disposed within said housing and carried by said packing, said sleeve being concentrically disposed with respect to said plunger and arranged to engage said housing, a collar having longitudinal recesses adjacent the longitudinally extending rows of teeth in said housing, the collar being slidably disposed within said housing and carried by said sleeve, and dogs disposed within the recesses in said collar and having ratchet teeth arranged to engage with the longitudinally extending rows of teeth in said housing to prevent movement of the collar in one direction with respect to said housing. 65

2. A deep well pump comprising a housing having longitudinally extending rows of teeth in its interior wall, a plunger having an enlarged portion at its uppermost end and arranged for movement in a reciprocatory path within said housing, a disk, packing carried by said disk, said packing being disposed between said plunger and said housing, a sleeve slidably disposed within said housing and carried by said packing, said sleeve being concentrically disposed with respect to said plunger and arranged to engage said housing, a collar having longitudinal recesses adjacent the longitudinally extending rows of teeth in said housing, the collar being slidably disposed within said housing and carried by said sleeve, dogs disposed within the recesses in said collar and having ratchet teeth arranged to engage with the longitudinally extending rows of teeth in said housing to prevent movement of the collar in one direction with respect to said housing, and a spring disposed within each of said recesses and arranged to bear against the dogs for yieldingly holding the latter in engagement with a portion of each of said longitudinally extending rows of teeth. 70 75 80 85
